WATER GRATE

Filed Nov. 20, 1926

WITNESS:

Pete Pritchel.

INVENTOR

John G. Gibson
BY
William J. Jackson
ATTORNEY.

UNITED STATES PATENT OFFICE

JOHN G. GIBSON, OF VENTNOR CITY, NEW JERSEY

WATER GRATE

Application filed November 20, 1926. Serial No. 149,565.

This invention relates to sectional water grates of a type for instance as disclosed in U. S. Letters Patent No. 1,366,377, dated Janauary 25, 1921.

5 In grates of the character shown in my aforesaid patent, experience has taught that the recessed bars are both difficult to make and are more or less expensive. Further, a relatively large upper bar surface is presented as compared to a relatively small, perforated surface for air delivery. A further fault resided in the time required to fit the numerous air tubes to place.

10 The leading object of the present invention is to overcome the above described disadvantageous features and provide a water grate construction which may be more cheaply manufactured and assembled and in which a relatively more air emitting surface is provided as compared with the upper grate bar surface.

15 A further object of the present invention is to provide an arrangement and construction of air delivery unit whereby one of my 20 novel units takes the place of a plurality of my former tubes so that not only are additional air vents provided but original installation and repairs may be more rapidly performed.

25 A further object is to provide a novel combination, arrangement, and connection of parts for attaining the results sought by the foregoing objects.

30 With these and other objects in view, the invention consists of the novel construction hereinafter described and finally claimed.

35 The nature, characteristic features and scope of the invention will be more fully understood from the following description 40 taken in connection with the accompanying drawings forming part hereof, and in which:

Fig. 1, is a view in plan of my novel grate bar.

45 Figure 2, is a view in perspective of one of the air delivery units detached.

Fig. 3, is a view in section taken upon the line 3—3 of Fig. 1.

50 Fig. 4, is a view in section taken upon line 4—4 of Fig. 1; and

Fig. 5, is a view in section taken upon line 5—5 of Fig. 1.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

5 In the drawings the reference numeral 1 designates a plurality of spaced, hollow grate bars going to make up a so-called water-grate. The opposed faces of these bars are each provided at their bottoms with continuous flanges 2 to support between said bars a plurality of air delivery units 3. The units as shown in Fig. 2, are of cube shape, are hollow, and have open bottoms 4 and perforated domes 5. These units are provided at their bottoms with opposed flanges 6. The units are positioned between the bars so that the flanges 6 abut as clearly seen in Fig. 5. The units are maintained in place by means of cementitious material 7, best seen in Fig.

5 As is very clearly seen in Fig. 3, the cross-sectional area of a bar 1 is approximately but one-half the cross-sectional area of a unit whereas in my aforesaid patent the air tubes are of much less dimension, considered in cross-section.

By my novel construction of cube-like air units a large amount of air vents are spread generally over the grate surface instead of in a restricted area, the advantages of which are apparent. Also,

by reason of the configuration of units and bars they can be more readily and cheaply positioned and lend themselves more readily to convenient storage and shipment. The top edges of the bars are bevelled as at 8, see Fig. 3, and the ends of the units facing said bevelled parts 8 are tapered off at 9 so that the inclined apertures 10 are free to spread air jets across the top surfaces of the bars 1.

What I claim is:

In a grate of the character stated, a plu-

rality of spaced, parallel, hollow grate bars of relatively narrow cross-section, opposed bottom edges of which are provided with laterally extending flanges, a plurality of substantially cubical units the top edges of which are bevelled, said units being supported on said flanges, said units being of relatively large cross section having open bottoms and perforated domes, some of which perforations are formed at an angle to the unit side walls and passed through said bevelled parts, opposed flanges at the unit bottoms with said unit flanges abutting to form a space between adjacent units, there being also a space between the units and the outer walls of said grate bars, and cementitious material filling the space around each unit, the top surface of which cementitious material is in a plane below the dome tops so that the perforations formed in said bevelled edges are free to discharge air above the top surface of the cementitious material.

JOHN G. GIBSON.
